UNITED STATES PATENT OFFICE.

ARTHUR W. FERRIN, OF KEYPORT, NEW JERSEY, ASSIGNOR, BY MESNE ASSIGNMENTS, TO NEW JERSEY MOTORS, INC., OF KEYPORT, NEW JERSEY, A CORPORATION OF NEW JERSEY.

ENGINE STARTER.

Application filed December 22, 1922. Serial No. 608,405.

To all whom it may concern:

Be it known that I, ARTHUR W. FERRIN, a citizen of the United States of America, and a resident of Keyport, county of Monmouth, and State of New Jersey, have invented certain new and useful Improvements in Engine Starters, of which the following is a specification.

This invention relates to manually operable starting mechanism for internal combustion engines.

Most of the manually operable starting mechanisms for internal combustion engines include pawls, ratchets and other parts that revolve continuously during the operation of the engine. This has been found to be objectionable since the parts are apt to become loose and rattle and also become worn and in most cases rust in position making them useless.

This invention has for its object to provide an engine starting mechanism so constructed and arranged that none of the operative parts thereof will continue in motion after the engine has started.

Another object of the invention is to provide a starting mechanism that is simple and practical in construction and efficient in operation.

Further objects of the invention will appear from the following specification taken in connection with the drawings, which form a part of this application, and in which

Fig. 1 is a longitudinal sectional view of an engine starting mechanism constructed in accordance with the invention.

Fig. 2 is an elevation taken at right angles to Fig. 1, and

Fig. 3 is a sectional detail view taken substantially on line 3—3 of Fig. 2.

The invention briefly described consists of mechanism adapted for connection to an engine shaft comprising a starter shaft, a pair of sprocket wheels, one mounted on the starter shaft and the other on a bearing on the engine shaft and means including levers between the sprocket wheels for operatively connecting the engine shaft sprocket wheel to the shaft when the starter shaft and sprocket wheel thereon are moved bodily by the starting crank. The operative connection between the sprocket wheel on the engine shaft and the shaft is so constructed that after the engine has been started, the sprocket wheel will be automatically

disconnected from the shaft and also means has been provided for returning the lever mechanism to its initial position upon the release of the starter shaft and crank. Further details of the invention will appear 60 from the following description.

Referring to the drawings, there is illustrated a portion of the engine or crank shaft 10 and crank casing 11. A sprocket wheel 12 encircles the shaft 10 and is rotatably 65 mounted on a bearing member 11^A secured to the crank casing 11. The sprocket wheel has formed therein diametrically opposite depressions 13 having shoulders 14 for engagement by end portions 15 of a pin 16 secured to the shaft 10. From the showing particularly in Fig. 3, it will be noted that the depressions 13 in the sprocket wheel have curved or cam surfaces 17 for the purpose of permitting the end portions 15 of the pin 70 16 to ride out of the depressions after the engine has been started and the portions 15 of the pin are curved as shown at 18 to facilitate this action.

The sprocket wheel 12 is connected by a 80 chain 20 to a sprocket wheel 21 fixedly secured to the starter shaft 22. The shaft 22 is mounted in bearings 23 formed in opposite walls 24 and 25 of a casing 26 secured to the crank case 11. A crank handle 27 is mounted on one end of the shaft 22 and the shaft is mounted for longitudinal as well as rotational movement in the bearings 23.

The means for operatively connecting the sprocket wheel 12 to the shaft 10 comprises 90 a pair of levers 28 and 29 pivoted respectively on pivots 30 and 31 in casing 26.

The lever 28 has one end 32 engaging one face of the sprocket wheel 21 and the opposite end of this lever engages an extension 95 33 formed on the lever 29.

The opposite end of the lever 29 is bifurcated as shown at 34 and this forked end portion is disposed in an annular groove 35 formed in the hub 36 of the sprocket wheel 12. A spring 37 encircles the pivot 31 of the lever 29 and engages the lever at one end and at its opposite end abuts against the wall 25 of the casing 26. This spring normally retains the lever in the position shown in 100 Fig. 1 and returns the lever to this position when the handle 27 and shaft 22 and sprocket wheel 21 are released by the operator.

The starting mechanism operates in the 110

following manner. In order to start the engine the operator grasps the handle 27 and pushes the handle in a direction to move the shaft 22 into the casing 26 or to the right viewing Fig. 1. This longitudinal movement of the shaft will also move the gear 21 and the movement of the gear will swing the lever 28 about its pivot, thereby swinging the lever 29 in an anticlockwise direction and moving the sprocket wheel 12 toward the pin 16 carried by the shaft 10. The operator will then rotate the handle 27 in an anticlockwise direction, thereby turning over the engine. If desired, the pin and sprocket can be so relatively arranged as to start the engine by a clockwise rotation of the crank handle. When the engine has been started, the ends 15 of the pin 16 will automatically ride out of the depressions 13 in the sprocket wheel 12 and release of the handle 27 by the operator will cause the spring 37 to swing the lever 29 in a clockwise direction, thereby moving the sprocket wheel 12 away from the pin 16 and returning the parts to the position shown in Fig. 1. It will be understood that although the starting mechanism has been shown and described as mounted on the crank case and connected to the motor shaft, it could be mounted on a reverse gear and connected through such mechanism to the shaft.

Although one specific embodiment of the invention has been particularly shown and described, it will be understood that the invention is capable of modification and that changes in the construction and in the arrangement of the various cooperating parts may be made without departing from the spirit or scope of the invention as expressed in the following claims.

What I claim is:

1. Engine starting mechanism comprising a starter shaft, an engine shaft, a bearing on the engine shaft, a sprocket wheel on the starter shaft and a sprocket wheel rotatably mounted on the bearing surrounding the engine shaft, a chain connecting said wheels and lever means between said sprocket wheels, operable upon movement of one of said wheels to operatively engage the other wheel with said engine shaft.

2. Engine starting mechanism comprising a starter shaft, an engine shaft, a bearing on the engine shaft, a sprocket wheel on the starter shaft and a sprocket wheel rotatably mounted on the bearing surrounding the engine shaft, a chain connecting said wheels and means, including a plurality of levers, between said sprocket wheels, operable upon movement of one of said wheels to operatively engage the other wheel with said engine shaft.

3. Engine starting mechanism comprising a longitudinally movable starter shaft, an engine shaft, a bearing on the engine shaft,

a sprocket wheel on the starter shaft and a sprocket wheel rotatably mounted on the bearing surrounding the engine shaft, a chain connecting said wheels and lever means between said sprocket wheels, operable upon longitudinal movement of the starter shaft and the wheel carried thereby to operatively engage the other sprocket wheel with the engine shaft. 70

4. Engine starting mechanism comprising a longitudinally movable starter shaft, a sprocket wheel fixed thereto, an engine shaft, a bearing surrounding said engine shaft, a sprocket wheel loosely mounted on the bearing and adapted to operatively engage said engine shaft, a lever having one end movable by the sprocket wheel on the starter shaft and means movable by said lever for operatively connecting the engine shaft and the other sprocket wheel. 80 85

5. Engine starting mechanism comprising a longitudinally movable starter shaft, a sprocket wheel fixed thereto, an engine shaft, a bearing surrounding said engine shaft, a sprocket wheel loosely mounted on the bearing and adapted to operatively engage said engine shaft, a lever having one end movable by the sprocket wheel on the starter shaft and a lever movable by said lever for operatively connecting the engine shaft and the other sprocket wheel surrounding the shaft. 90 95

6. Engine starting mechanism comprising a longitudinally movable starter shaft, a sprocket wheel fixed thereto, a casing, a second shaft, a sprocket wheel rotatably and slidably mounted on a fixed portion of the casing surrounding said shaft, and means set in operation by the longitudinal movement of the starter shaft and wheel fixed thereto for operatively engaging said second sprocket wheel with said shaft. 100 105

7. Engine starting mechanism comprising a longitudinally movable starter shaft, a sprocket wheel fixed thereto, a casing, a second shaft, a sprocket wheel rotatably and slidably mounted on a fixed portion of the casing surrounding said shaft, and means set in operation by the movement of said first sprocket wheel for operatively engaging said second sprocket wheel with said shaft. 110 115

8. Engine starting mechanism comprising a longitudinally movable starter shaft, a sprocket wheel fixed thereto, a second shaft, a casing surrounding the second shaft, a sprocket wheel rotatably and slidably mounted on a fixed portion of said casing and adapted to operatively engage said second shaft, means for operatively connecting said sprocket wheels and means for maintaining all parts of the starting mechanism out of contact with moving parts of the engine when the mechanism is not in operation. 120 125

In witness whereof, I have hereunto set my hand this 20th day of December, 1922.

ARTHUR W. FERRIN.
